DEESTERIFICATION OF AROMATIC COMPOUNDS

James D. Head, Midland, Mich., assignor to The Dow Chemical Company, Midland, Mich., a corporation of Delaware

No Drawing, Application December 23, 1949,
Serial No. 134,838

4 Claims. (Cl. 260—623)

1

This invention relates to the de-esterification of aromatic compounds, and, more particularly, to a method for de-esterifying or freeing saligenin or a substituted-saligenin from saligenin diacetate or a substituted-saligenin diacetate.

The need for the discovery of a relatively inexpensive method for producing 3-fluorosalicylaldehyde has recently appeared. The need arose as a result of the work of Tsumaki (see J. Chem. Soc. Japan, 58, 1288 (1937)) and Calvin (see J. Am. Chem. Soc. 68, 2254 (1945)); Tsumaki showed that the cobalt chelate of the Schiff's base from salicylaldehyde and ethylene diamine would absorb oxygen and that the absorption was reversible, and Calvin found that the cobalt chelate of the Schiff's base from 3-fluorosalicylaldehyde and ethylene diamine was particularly advantageous as providing a convenient means for separating oxygen from the nitrogen of the air. A search for an inexpensive method for producing 3-fluorosalicylaldehyde resulted in the discovery of an efficacious way of producing 5-chloro-3-fluorosaligenin diacetate and related compounds. However, attempts to de-esterify the diacetates produced by this method by ordinary means proved unsuccessful. The compounds are sufficiently sensitive to strong reagents and elevated temperatures that de-esterification could not be accomplished in reasonable yields by ordinary methods.

The principal object of the invention is to provide a method for de-esterifying saligenin diacetate and substituted saligenin diacetates. More specific objects and advantages are apparent from the description which illustrates and discloses but does not limit the invention.

According to the invention the diacetate of a 1-hydroxymethyl-2-phenol is de-esterified. The de-esterification is accomplished by refluxing a mixture of the diacetate of the 1-hydroxymethyl-2-phenol with methanol in the presence of a strong mineral acid, and distilling low-boiling material formed until the head temperature reaches the boiling temperature of methanol. The structure of the compounds that are de-esterified according to the invention may be more clearly understood by reference to the following schematic formula:

2

The rest of the structure of the material that is de-esterified in the practice of the invention is relatively unimportant. Each substituent, if any, is attached to the 3-, 4-, 5-, or 6-carbon atom. It is usually preferred that any substituent be a halogen, a lower alkyl or lower alkoxy radical, a phenyl or phenoxy radical, or an aralkyl, alkaryl, alkaroxy, or aralkoxy radical having not more than ten carbon atoms. ("Lower alkyl," and "lower alkoxy," as used herein, refer to radicals having not more than four carbon atoms.)

As is hereinbefore indicated, the 1-hydroxymethyl-2-phenol is de-esterified according to the invention by refluxing a mixture thereof with methanol. It is important that a relatively large ratio of methanol to the diacetate of the 1-hydroxymethyl-2-phenol be employed in the practice of the invention. The 1-hydroxymethyl-2-phenols are heat sensitive; accordingly, the amount of methanol employed is the sum of (1), the amount required to carry out the de-esterification (which is believed to form two mols. of methyl acetate per mol of the diacetate de-esterified), (2) the amount lost from the solution during the distillation of the methyl alcohol-methyl acetate azeotrope, B. P. 54° C., and (3) an amount of methanol sufficient to maintain the 1-hydroxymethyl-2-phenol in solution without over-heating, in the course of the reaction. Ordinarily it is essential that the mol ratio of methanol to the diacetate be at least about 10:1. Usually, it is economically disadvantageous that the mol ratio be higher than about 25:1, and most desired that it be about 20:1.

Although it is possible to conduct the de-esterification of the invention under reduced pressure, this is ordinarily undesirable because of the increased cost involved. Superatmospheric pressures, because of the increased temperatures involved, are disadvantageous. Accordingly, the best procedure usually is to carry out the de-esterification at atmospheric pressure. The material volatilized in the early part of the de-esterification is principally the methyl alcohol-methyl acetate azeotrope. The material vaporized is removed slowly from the reaction vessel. When the vapor temperature rises substantially above the boiling point of the azeotrope (e. g., from 4° C. to 5° C. above), all vapors are condensed, and the condensate returned to the reaction vessel (i. e., total reflux is used). If the removal of vapors has been sufficiently fast that a substantial proportion of the azeotrope remains in the reaction vessel, the temperature of the vapors will drop substantially to the boiling tem-

perature of the azeotrope; if not, the temperature will remain approximately constant when the removal of vaporized material is discontinued. Removal from the system of materials vaporized is continued until there is no indication of the presence of additional low boiling azeotrope, after which point in the distillation a small quantity of vapor is removed until the head temperature reaches the boiling temperature of methyl alcohol. De-esterification is then found to have proceeded to such an extent that the pure 1-hydroxymethyl-2-phenol can be recovered by pouring the reaction mixture into distilled water. The desired product crystallizes in a pure form.

As is heretofore stated, the de-esterification is accomplished in the presence of a strong mineral acid. It is usually preferred that the strong mineral acid that is used be one sufficiently soluble in the reaction solution that it is not distilled therefrom in the course of the refluxing; otherwise, additions of the acid must be made during reaction. Sulfuric acid and sulfonic acids are particularly desirable, especially aryl sulfonic acids (e. g., benzene sulfonic acid, toluene sulfonic acids, xylene sulfonic acids, and the like). The amount of the strong mineral acid that is used may vary from about 0.5 per cent to about 3 per cent. (The terms "per cent" and "parts" are used herein to refer to per cent and parts by weight unless otherwise indicated.) It is usually preferred that the amount of strong mineral acid employed be about 1 per cent of the diacetate present.

The method of the invention is particularly advantageous because of the characteristics of the 1-hydroxymethyl-2-phenols and their diacetates. The heat sensitivity of these compounds not only makes de-esterification by ordinary means impractical, but also makes purification (e. g., by recrystallization or distillation) of the 1-hydroxymethyl-2-phenol virtually impossible. Accordingly, if it is desired to obtain a pure product, it is necessary to conduct a slow de-esterification so that substantially quantitative reaction is achieved.

The following examples illustrate, but are not to be construed as limiting the invention:

Example 1

According to the invention the diacetate of a 1-hydroxymethyl-2-phenol was de-esterified according to the following procedure:

5 - chloro - 3 - fluorosaligenin diacetate¹ (260 grams), methanol (1200 cc.) and benzene sulfonic acid (1 gram) were mixed and heated to reflux. A slow distillation through a four foot column (using a reflux ratio of 30:1) was then started. This distillation was discontinued when the head temperature of the vapors exceeded 64° C., at which time the total distillate (principally the methyl alcohol-methyl acetate azeotrope) amounted to 900 cc. The residue in the still was then diluted with water to make a total volume of three liters. A few seed crystals of previously prepared 5-chloro-3-fluorosaligenin were added thereto, and the desired product, which crystallized immediately, was separated from the liquid by filtration and was air dried. Further product

was crystallized by making the filtrate slightly alkaline, concentrating it to a volume of 500 cc., acidifying, and adding a few seed crystals of 5-chloro-3-fluorosaligenin. The total recovery of 5-chloro-3-fluorosaligenin amounted to 175 grams, which corresponds to a 99 per cent yield based upon the 5-chloro-3-fluorosaligenin diacetate used.

Example 2

A procedure similar to that described in Example 1 was used to de-esterify 3,5-dichlorosaligenin diacetate. The 3,5-dichlorosaligenin diacetate (138 grams), methanol (250 grams) and benzene sulfonic acid (0.1 gram) were refluxed and the azeotrope was distilled. When the methyl acetate had been distilled, cold water (1500 cc.) was added to the residue in the still. White crystals of 3,5-dichlorosaligenin precipitated immediately and were recovered in pure form and in a substantially theoretical yield by filtration and air drying.

I claim:

1. A method of de-esterifying 5-chloro-3-fluorosaligenin diacetate which comprises heating a mixture thereof with methanol at a refluxing temperature in the presence of a strong acid, and distilling low-boiling material formed until the head temperature reaches the boiling temperature of methanol.

2. A method of de-esterifying 3,5-dichlorosaligenin diacetate which comprises heating a mixture thereof with methanol at a refluxing temperature in the presence of a strong acid, and distilling low-boiling material formed until the head temperature reaches the boiling temperature of methanol.

3. A method of de-esterifying a 3,5-dihalosaligenin diacetate which comprises heating a mixture thereof with methanol at a refluxing temperature in the presence of a strong acid, and distilling low-boiling material formed until the head temperature reaches the boiling temperature of methanol.

4. A method of de-esterifying the diacetate of a 1-hydroxy methyl-2-phenol corresponding to the formula

wherein each of the positions 3, 4, 5, and 6 is substituted with a member of the group consisting of hydrogen, halogen, lower alkyl, lower alkoxy, phenyl, phenoxy, aralkyl, alkaryl, alkaroxy and aralkoxy, each of the four latter radicals containing not more than ten carbon atoms, that comprises heating a mixture of such diacetate with methanol at a refluxing temperature in the presence of a strong acid, and distilling low-boiling material formed until the head temperature reaches the boiling temperature of methanol.

¹ The preparation of 5-chloro-3-fluorosaligenin diacetate is disclosed in the application of Edgar C. Britton and James D. Head entitled "Production of 3-fluorosalicyl-aldehyde" filed concurrently herewith, now U. S. Patent 2,576,064.
